WINDMILL CONSTRUCTION

Filed Jan. 19, 1931

18 Inventor:
John S. Baker,
By Edmund Parker & S. Atty's.

UNITED STATES PATENT OFFICE

JOHN S. BAKER, OF EVANSVILLE, WISCONSIN

WINDMILL CONSTRUCTION

Application filed January 19, 1931. Serial No. 509,807.

This invention relates to improvements in windmills and has more particular reference to the construction of the swivel connecting the furling chain and the pull cord so that the mill may be brought into and out of the wind in any angular position of the mill relative to its supporting tower.

The general object of the invention is to provide a new and improved windmill swivel which is simple and inexpensive in construction, reliable in operation, and capable of withstanding the severe stresses to which it may become subjected in service.

More specifically stated, the invention resides in the novel character of the swivel proper which enables the swiveling action between its rotatable and non-rotatable parts to be produced by spiraling of the furling chain while under tension.

Another object is to provide a novelly constructed bail constituting a force-transmitting connection between the non-rotatable member of the swivel and the pull cord by which the mill is furled.

Other objects and advantages of the invention will become apparent from the following detailed description taken in connection with the accompanying drawing, in which

Figure 1 is a fragmentary elevational view of the upper portion of the tower of a windmill equipped with a swivel embodying the features of the present invention.

Fig. 2 is a view similar to Fig. 1 looking from the left thereof.

Fig. 3 is a view similar to Fig. 2 showing the non-rotatable part of the swivel in section.

Fig. 4 is a section taken respectively along the line 4—4 of Fig. 2.

While the invention is susceptible of various modifications and alternative constructions, I have shown in the drawing and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

In the exemplary form of the invention illustrated in the drawing, the numeral 5 indicates a casing housing the operating parts

of the windmill and rigid with a tubular mast or pivot tube in the form of a pipe 6 through which the pump rod 7 reciprocates. The mast is mounted to turn about its longitudinal axis in the upper end of the tower which is composed of upwardly converging angle bars 8. The swivel to which the present invention is directed provides a force-transmitting connection between a pull cord 9 which extends to a point adjacent the ground and the furling chain 10 which extends upwardly along the pivot tube and around sheaves 11 for connection in the usual manner with the arm which carries the windmill vane (not shown).

The swivel proper, which is located above the upper end of the tower and is free to reciprocate longitudinally of the tube 6 is composed of a non-rotatable member in the form of a ring 12 and a rotatable member in the form of a semi-circular segment 13. The latter lies flat against the external surface of the tube and is thus adapted to slide longitudinally thereof while the mill is being furled or unfurled, at the same time being free to turn relative to the tube. The lower end of the furling chain 10 may be attached to the segment through the medium of an outwardly projecting lug 14 integral with the segment.

In the present instance, the ring 12 is composed of two separate segments whose adjacent ends have outwardly projecting lugs 15 and are adapted to be clamped together by bolts 16. At its upper edge each segment of the ring has an inturned flange 17 defining a central circular recess which is of such diameter that the segment 13 projects freely through the ring when the latter is encircling the tube 6. Beneath the flange 17, the segment 13 is formed with an integral horizontal flange 18 which cooperates with the flange 17 to provide for relative swiveling between the rotatable and non-rotatable members above the pivotal axis of the mill.

Means is provided for transmitting the actuating force from the pull cord 9 to the swivel and for holding the ring 12 against turning. This means comprises a U-shaped bail 19 having a horizontally extending closed end disposed within the tower structure and two upwardly extending parallel legs 20. In order to give the bail strength to resist all of the forces to which it may be subjected in service, it is preferably formed from a

narrow strip of flat sheet metal stock. Initially, the end portions of the strip are bent edge-wise to form the closed end of the bail, the central portion of which is bent into a semi-circle to conform to the curvature of the lower end of the mast as shown in Fig. 4. This leaves radially projecting portions 21 and the legs 20 disposed in a vertical plane including the pivotal axis of the mill, so that 10 with the pull cord 9 attached to the portions 21 the actuating force applied thereby acts substantially along the swiveling axis of the mill.

With the bail thus partially formed, its legs 15 20 are twisted through an angle of ninety degrees so that their upper ends are disposed at right angles to the portions 21. The extreme upper ends of the legs project into spaces between the lugs 15 and are suitably 20 bent so that they may be firmly clamped between the lugs by the bolts 16.

Assuming that the linkage is under tension with the parts positioned as shown in Fig. 3, the action of the swivel is as follows. Inasmuch as the lug 14 is projecting at right angles to the bail legs 20, the reaction of the furling chain tends to tilt the ring 12 in a direction to place the upper ends of the legs 20 under severe bending stress. But the legs, 30 being disposed edgewise to the line of action of this force, are strong to resist such bending.

Now, as the windmill head and the pivot tube 6 turn relative to the tower, the ring 12 is held against movement by the bail on which 35 the tower bars 8 act as stops and turning of the segment 13 is resisted by friction between the flanges 17 and 18. Thus the chain 10 becomes inclined or spiraled around the tube 6 thereby exerting a torsional force tending 40 to turn the segment 13 relative to the ring 12. Such spiraling continues as the head turns until the torsional force due to such spiraling overcomes the friction between the flanges whereupon the segment turns slightly 45 in the same direction as the windmill head. Thus, the swiveling action is produced by spiraling of the furling chain when under tension.

When the segment 13 has turned sufficient- 50 ly to bring the lug 14 into the plane of the legs 20 as shown in Fig. 1, the force tending to tilt the ring 12 exerts a distorting action on the bail by tending to shift one leg thereof longitudinally relative to the other leg. The 55 closed end of the bail being disposed in a vertical plane is strong to resist such force and effectively prevents distortion of the bail.

It will be apparent that I have provided 60 a swivel of exceedingly simple construction, which is adapted for use with pull-in or pull-out windmills, and which effectively resists

the various distorting stresses to which it becomes subjected in service.

I claim as my invention:

1. In combination with a windmill tower and a vertically extending pipe swiveled in and projecting above the upper end of said tower, a swivel including a ring encircling said pipe above the upper end of said tower, and a U-shaped bail composed of flat metal stock with its closed end disposed within said tower and lying flat against said pipe so that the major portion of the bail is disposed in a plane including the axis of said pipe, the legs of said bail projecting upwardly through the tower and attached to opposite sides of said ring, said ends being twisted through a right angle relative to said closed end. 70 75 80

2. In combination with a windmill tower and a vertically extending pivot tube swiveled in and projecting above the upper end of the tower, a swivel including a ring encircling said tube above the upper end of said tower, and a U-shaped bail composed of a flat metal strip bent edgewise into a U-shape with its closed end disposed within said tower and connected to the pull cord of the windmill, the extreme ends of the legs of the bail being twisted relative to said closed end through a right angle and attached to said ring. 85 90 95

3. In combination with a windmill, a non-rotatable swivel ring disposed in horizontal position and encircling the vertical pivotal axis of the windmill, an upwardly opening U-shaped bail having a horizontally extending intermediate portion adapted to resist vertical bending, and flat vertical legs with the upper ends disposed parallel to each other so as to resist bending in a horizontal direction, said ends being attached to opposite sides of said ring. 100 105 110

4. In a windmill furling swivel, a bail formed from a flat metal strip bent endwise into a U-shape with its legs twisted relative to the closed end of the bail so as to resist lateral bending. 110

5. In a windmill the combination of a tower and a vertically extending pivot tube projecting above the upper end thereof, a furling chain extending downwardly along said tube above the upper end of said tower, a ring encircling said tube and adapted to be actuated by the pull cord of the windmill, a member disposed adjacent said tube and cooperating with said ring to form a swivel, said member being attached to the lower end of said chain so that the swiveling action between the ring and said member is produced by spiraling of the chain about said tube. 115 120 125

In testimony whereof, I have hereunto affixed my signature.

JOHN S. BAKER.

CERTIFICATE OF CORRECTION.

Patent No. 1,917,631.

July 11, 1933.

JOHN S. BAKER.

It is hereby certified that error appears in the printed specification of the above numbered patent requiring correction as follows: Page 2, line 115, claim 5, strike out the words "above the upper end of said tower" and insert the same after "tube" in line 116; and that the said Letters Patent should be read with this correction therein that the same may conform to the record of the case in the Patent Office.

Signed and sealed this 24th day of October, A. D. 1933.

F. M. Hopkins
